FOLDING IRONING BOARD

Edwin E. Foster, Austin, Tex.

Application May 10, 1949, Serial No. 92,345

10 Claims. (Cl. 38—117)

1

The present invention relates to a folding ironing board and iron mount or unit in which the ironing board is foldable and the iron mount and iron is a separate unit applicable to the ironing board to be removable therefrom.

It is an object of the present invention to provide an ironing board with legs pivotally mounted to a base and to the board which together form a parallelogram movement so that the board may be shifted horizontally relative to the operator. A further object of the invention resides in the provision of means on the base to limit the movement of the board horizontally in its extreme limits of movement in both directions. A still further object of the invention resides in the provision of means to mount an iron on the base to movably support the iron over the board and to counterbalance the iron. Also the limit stops for the horizontal movement of the board include means automatically releasable when the board and frame are tilted on the floor by actuating a trigger mechanism to permit the board and frame with the legs to be folded in a flat configuration.

Another object of the invention resides in a base member for the iron to not only support a post for the iron but also to hold the iron and arm when not in use.

Further objects will be apparent from the following description when considered in connection with the accompanying drawings in which:

Figure 1 is a side elevation of the ironing board and its supporting structure or frame,

Fig. 2 is a cross section taken on line 2—2 of Fig. 1 in the direction of the arrows,

Fig. 3 is a cross section taken on line 3—3 of Fig. 1 in the direction of the arrows,

Fig. 4 is a bottom elevation showing the board in the folded position and taken in the plane of line 4—4 of Fig. 5 in the direction of the arrows,

Fig. 5 is a side elevation showing the board in the folded position and taken in the plane of line 5—5 of Fig. 4 in the direction of the arrows,

Fig. 6 is a side view partly in section of a detail of the holding stop,

Fig. 7 is a plan view of the holding stop taken in the plane of line 7—7 of Fig. 6 in the direction of the arrows,

Fig. 8 is a bottom plan view of a portion of the frame,

Fig. 9 is a top plan view of the iron support and base,

Fig. 10 is a side view of the iron support,

Fig. 11 is an end view of the iron support,

2

Fig. 12 is a perspective view of the ironing board and its support together with the iron support, and

Fig. 13 is a side elevation of the iron support in its stored or non operative position.

Referring to Figs. 1 to 5 and 12 any suitable type of ironing board 2 may be used and this board may be made of wood or metal such as stainless steel, aluminum, or any other metal or alloy. This board 2 is supported by a pair of preferably tubular legs 3 and 4 pivotally mounted on a rod 5, Fig. 4, in a cross brace 6 at the pivot points 7, 9, 11, 12 and a third tubular leg 8 pivotally secured at 9 to the underside of the board 2. A U-shaped base frame 10 also of tubular construction has the legs 3 and 4 pivotally connected thereto at 11 and 12 respectively and the leg 8 is pivotally connected to the frame 10 at 13. As seen in Figs. 2 and 4 the legs 3 and 4 may be provided with tubular cross braces 29 suitably secured such as by welding to the legs. All of the pivoted connections 7, 9, 11, 12 and 13 are for the purpose to permit the board 2 to be shifted laterally from the full line position 15 Fig. 12 to the dash line position 14 so that an operator may sit before the ironing board and at the same time reach the entire top area of the board without getting up or shifting positions by merely adjusting the board 2 longitudinally. Furthermore the pivotal connections 20 permit the board and legs to be folded into the position of Fig. 5, as will be described.

In order to limit the movement of the ironing board 2 relative to the base 10, a latch or holding stop member 15 is secured at one end to the leg 8 and the other end to the base frame 10 at 16, Fig. 12. Figs. 6 to 8 illustrate the specific structure of the holding stop member on an enlarged scale. A piston rod 17 is provided at one end with an eye member 18 and a piston 19 at the other end acting as an abutment. The piston rod 17 reciprocates in a cylinder 20 pivotally mounted by a pin or bolt 21 on ears 22 secured on the frame 10.

Movement of the piston to the left in the cylinder is limited by engagement of the piston with the left end of the cylinder. Movement of the piston to the right is limited by a latch member 23 in the form of a yoke pivoted on the pin 21 and having a crosspiece 26 movable through an opening 27 in the cylinder into the path of movement of the piston. A spring 28 connected to the latch member and the end of the cylinder urges the latch member inward to its latching position.

To release the latch for folding of the board

an operating lever or trigger 24 is provided pivoted at 25 on the base frame 10. One end of the lever 24 fits into an opening in the latch member 23 which is spaced to one side of the pivot pin 21 as shown in Figure 8. When the latch is swung in to its latching position the lever 24 will be swung outward from the base frame as shown in Figure 12. When the lever 24 is pressed in toward the base frame it will swing the latch away from the cylinder and out of the path of the piston so that the frame can be folded.

The frame 10 is also provided with a short projecting socket member 29, Fig. 1, which receives the iron mount 30, Figs. 9 to 13, and this mount is provided with a depending pin 31 adapted to fit into the socket as shown in Fig. 12. The mount 30 is provided with a top surface 32 having a depressed portion 33 into which an iron 34 fits and rests when the mount and its iron are in a non-ironing or stored position as shown in Fig. 13. The iron 34 is mounted and secured to an articulated arm 35 which is illustrated and described in my co-pending application Serial No. 669,318, filed May 13, 1946, now abandoned.

The iron mount 30 is also provided with an upstanding tubular column or tube 36 into which a spindle 37 of the arm 35 may be inserted, Fig. 12. In the position of Fig. 12 the various parts and sections are set up ready for ironing but the assembly shown in Fig. 13 illustrates the iron with its arm and the mount adjusted in position to be stored away.

As described and illustrated in the said co-pending application the arm 35 is preferably in two parts 38 and 39 pivoted at 40 and also pivoted to the spindle 37. The arm is provided with means to counterbalance the arm and iron as shown in the said co-pending application.

As to the operation of the board 2 and its use as well as the manner in which it can be folded, it is quite clear from the drawings and the description as to how the various parts operate and function. As already pointed out the board is particularly useful in ironing with the operator seated on the far side of the board in the position shown in Fig. 12. As the board is longitudinally movable, that is parallel to the longitudinal axis of the board, by moving the board between the full and dash lines the entire board may be reached by the operator. The latch shown in Figs. 6 and 7 limits the movement of the board.

When the operator is through with the ironing, the board may be folded flat to the position shown in Figs. 4 and 5 and the iron with its mount assembled in the position of Fig. 13 so that both sections may be stored away in a minimum of space. In folding and packing the iron mount it is merely necessary to lift the pin 37 out of the tubular post 36, Figs. 12 and 13, and place the pin 37 in the perforation 66 in the base portion 30 with the iron resting in the depressed portion 33. The entire assembled iron and mount may now be lifted out of the hole 29, Fig. 1, and lifted from the pipe section 10. In folding the board from the position of Fig. 12 the left end of the board may be raised with the right end frame 10 bearing on the floor so that when the latch trip lever 24 touches the floor the latch will be released so that the various parts will fold together into the position of Figs. 4 and 5. The sections shown in the positions of Figs. 13 and 5 are now ready to be

stored away and it will be noted that the board of Fig. 5 will take up very little room.

I claim as my invention:

1. A support for ironing board comprising a U-shaped base frame adapted to rest on a floor, a pair of legs having cross braces and pivotally connected at one end to one arm of the frame on axes parallel to the arm, a single leg pivotally mounted at one end to the frame adjacent to its other arm, an ironing board pivotally connected on the other ends of the legs on axes transverse to its length for longitudinal shifting movement relative to base frame, and relatively movable elements connected to the frame and one of the legs and having interengaging parts thereon to limit their relative movement thereby to limit longitudinal shifting of the board.

2. A support for an ironing board according to claim 1, in which the base frame and legs are composed of tubular members.

3. A support for an ironing board according to claim 1, in which one of said interengaging parts is mounted for movement out of the path of another so that the board may be folded relative to the base frame and the legs.

4. A support for an ironing board according to claim 3, in which the latch is provided with a trigger on the base frame positioned to engage the floor and operate the latch when the base frame is tilted.

5. A support for an ironing board comprising a base adapted to rest on a floor, leg members pivoted on the base at longitudinally spaced points thereon on axes transverse to the base, an ironing board parallel to the base and pivoted on the other ends of the legs on spaced axes transverse to its length for longitudinal shifting relative to the base, a pair of slidably interfitting elongated members connected to the base and one of the leg members respectively for free longitudinal sliding relative to each other as the board shifts relative to the base, and spaced interengaging parts on the elongated members to limit the relative longitudinal sliding thereof thereby to limit said shifting of the board.

6. The construction of claim 5 in which one of the parts is retractable to an ineffective position, a spring normally urging said one of the parts to its effective position and operating means to move said one of the parts to its ineffective position.

7. The construction of claim 5 in which one of the parts is retractable to an ineffective position, a spring normally urging said one of the parts to its effective position and an operating lever pivoted on the base to engage the floor when the base is tilted to move said one of the parts to its ineffective position.

8. A support for an ironing board comprising a base adapted to rest on a floor, leg members pivoted on the base at longitudinally spaced points thereon on axes transverse to the base, an ironing board parallel to the base and pivoted on the other ends of the legs on spaced axes transverse to its length for longitudinal shifting relative to the base, a telescopically interfitting cylinder and plunger connected to the base and one of the leg members respectively for free relative sliding movement as the board shifts relative to the base, and stop parts in the cylinder engageable with the plunger to limit relative sliding thereof thereby to limit shifting of the board.

9. A support for an ironing board comprising a base adapted to rest on a floor, leg members pivoted on the base at longitudinally spaced

points thereon on axes transverse to the base, an ironing board parallel to the base and pivoted on the other ends of the legs on spaced axes transverse to its length for longitudinal shifting relative to the base, a telescopically interfitting cylinder and plunger connected to the base and one of the leg members respectively for free relative sliding movement as the board shifts relative to the base, and stop parts in the cylinder engageable with the plunger to limit relative sliding thereof thereby to limit shifting of the board, means mounting one of the stop parts on the cylinder for movement to an ineffective position, and operating means to retract said one of the stop parts.
